UNITED STATES PATENT OFFICE.

OSCAR W. URBAN, OF WASHINGTON, DISTRICT OF COLUMBIA.

DESIGN FOR A FLOOR CHISEL.

60,183.

Specification for Design.

Patented Jan. 3, 1922.

Application filed February 18, 1921. Serial No. 446,192. Term of patent 14 years.

To all whom it may concern:

Be it known that I, OSCAR W. URBAN, a citizen of the United States of America, residing at Washington, in the District of Columbia, have invented a new, original, and ornamental Design for a Floor Chisel, of which the following is a specification, reference being had to the accompanying drawing, forming part thereof.

In the drawing,

Figure 1 is a perspective view showing one side of a floor chisel, showing my new design, and

Figure 2 is an elevational view of the opposite side thereof.

I claim:

The ornamental design for a floor chisel, as shown.

OSCAR W. URBAN.
